UNITED STATES PATENT OFFICE.

PORT W. ROW, OF HILLSBORO, ILLINOIS.

RAIL-JOINT.

No. 898,006.

Specification of Letters Patent.

Patented Sept. 8, 1908.

Application filed February 11, 1908. Serial No. 415,390.

To all whom it may concern:

Be it known that I, PORT W. Row, a citizen of the United States, residing at Hillsboro, in the county of Montgomery and State of Illinois, have invented certain new and useful Improvements in Rail-Joints, of which the following is a specification.

My invention relates to certain new and useful improvements in railway rail joints, and it has for its object the provision of means for connecting and supporting the ends of railway rails without the use of the bolts and fish-plates as ordinarily employed for this purpose, and which will obviate the necessity of the renewal of the angle bars and bolts, as well as the necessity of the tightening of the bolts from time to time.

A further object of my invention is the production of a connecting device, which in the case of street railways will obviate the necessity of the frequent taking up of the pavement in which the rails are laid, in order to tighten or renew the bolts securing the rails.

With these and other objects in view I have produced a connection for railway rails which will securely hold the same together, and will make a stiff, strong joint between the same.

In the accompanying drawing constituting a part of this application and wherein I have shown the preferred embodiment of my invention, Figure 1 is a perspective view of a pair of rails showing my improved joint applied thereto; Fig. 2 a side elevation, partly in central section of the rails and the connecting piece interposed between the ends of the rails; Fig. 3 is a plan view of the chair on which the ends of the rails are seated. Figs. 4 and 5 are perspective views of the meeting ends of two rails and showing the recesses therein, and Fig. 6 is a similar view of the connecting piece for the rails.

Corresponding numerals indicate like parts in the several figures.

1, 1 designate a pair of rails provided at their adjoining ends with screw-threaded recesses

2. The rails 1 are provided at their meeting ends with the enlargements 3 extending outwardly from the webs thereof and backwardly to a point beyond the bottom of the recesses 2.

4 is a connecting piece made of the size and contour of the rails 1, including the enlargement 2 thereon, and provided with exten-

sions 5, 5, with right and left hand screw threads thereon which screw into the apertures 2 in the end faces of the rails 1. The piece 4 may be made of any desired length as may be found necessary in the expansion or contraction of the rails. I have found it desirable to make said piece 4 in three sizes for this purpose.

6 designates a chair on which the ends of the rails and connecting piece intermediate of the ends of the same are seated. This chair is made on its inner edge with an upwardly and inwardly extending clamp 7, adapted to take over the outer flanges of the rails and to confine the same therein. The inner edge of the chair 6 has a plain upper surface and is provided therethrough with spike holes, the heads of the spikes when applied thereto taking over the inner flanges of the rails in a well known manner. The spike holes are also provided on the outer side of the chair, as shown, to secure that side of the same to the ties. The chair is thus securely spiked to the ties and extends beyond the joint of the rails and the intermediate connection section to a distance sufficient to properly support the same, and assists in securely holding them in proper relation.

While I have shown and described herein the preferred embodiment of my invention, I do not wish to be limited to the exact form so shown and described, as various modifications may be made in the details of construction without departing from the scope of my invention.

I claim:

1. In a device of the character described, a pair of rails having screw-threaded apertures in their ends, and a connecting piece having screw threaded extensions thereon and adapted to be screwed into said apertures, as set forth.

2. In a device of the character described, a pair of rails having screw-threaded apertures in their ends, and a connecting piece having extensions thereon provided with right and left hand screw-threads, and adapted to be screwed into said apertures, as set forth.

3. In a device of the character described the combination with a pair of rails provided at their adjacent ends with side extensions formed on the webs thereof, and provided in their ends with apertures, of a connecting device adapted to be interposed between the ends of said rails and having the same form

of said rails at their connecting ends, and provided with extensions adapted to enter the apertures therein, as set forth.

4. In a device of the character described
5 the combination with a pair of rails having side extensions formed in their webs at their meeting ends, apertures in their ends, and a connecting device adapted to be interposed between the ends of said rails; of a chair on
10 which the rails and their intermediate connecting device are seated, comprising a plate extending under the joint of the rails, said

chair having on one side thereof an inwardly extending clamp adapted to take over the flanges of the connecting rails and provided 15 at both of its edges with spike holes whereby the said chair may be spiked to the ties, as set forth.

In testimony whereof I affix my signature in presence of two witnesses.
